J. T. GARTON

FLOOR WAXER AND POLISHER

Filed August 21, 1923

INVENTOR.
J. J. Garton.
BY. J. Edward Markee.
ATTY.

UNITED STATES PATENT OFFICE.

JOHN T. GARTON, OF TORONTO, ONTARIO, CANADA.

FLOOR WAXER AND POLISHER.

Application filed August 21, 1923. Serial No. 658,626.

To all whom it may concern:

Be it known that I, JOHN T. GARTON, of the city of Toronto, in the county of York, Province of Ontario, Canada, a subject of the King of Great Britain, have invented 5 certain new and useful Improvements in Floor Waxers and Polishers, of which the following is a specification.

This invention relates to devices as shown 10 in my Canadian Patent No. 220,644 of July 11th, 1922, and which are used to apply wax to the floor and also to rub in the wax and polish the floor. While the device described and illustrated in the said patent is very satisfactory, there are a few points, however, which I desire to improve. These are:

1. The method of securing the wax pad holder to the tool carrier.
2. The method of securing the cloth on the wax pad.
3. The method of mounting the brush on the tool carrier.

It is also desirable to provide auxiliary supporting means for taking a portion of the weight of the machine from the wax pad, and thus regulating the supply of wax to the floor.

I attain my objects by means of the constructions hereinafter described and illustrated in the accompanying drawings in which—

Fig. 1 is a plan view of my improved waxer and polisher showing the waxing pads uppermost, but with one waxing pad removed;

Fig. 2 a longitudinal section of the same on the line 2—2 in Fig. 1;

Fig. 3 a similar view with the brushes uppermost taken on the line 3—3 in Fig. 1;

Fig. 4 a plan view of the pad support;

Fig. 5 a detail in cross section through the tool carrier;

Fig. 6 an end view of the handle; and

Fig. 7 a side view of one of the spring keepers.

1 is the frame of the device, and 2 the tool carriers which are slidable on rods 3 suitably supported in the frame. These tool carriers are actuated from a crank shaft 4 journalled at one end of the frame, and on

this crank shaft are secured the ground wheels 5.

To one side of each tool carrier is secured a brush 6, and to the other side is detachably connected a wax pad holder. In the prior 55 patent referred to, the wax pad holder was held in place by headed pins engaging in keyhole slots in the carrier.

In the present construction, however, the wax pad holder is provided with a spring 60 clip 32, the ends of which are adapted to engage shoulders 7 formed on the upper side of the carrier. Guards 8 are preferably cast on the under side of the pad holder to protect the clip 32. 65

In the top of the carrier I also form holes 9 and on the under side of the pad holder are formed the depending pins 10, which are adapted to project into the holes 9 and take the strain, when the device is being used, 70 from the clip 32.

From the construction described it will be seen that it only requires a straight pull to remove the pad holder from the carrier, thus eliminating the turning movement of 75 the earlier construction.

Superimposed on the pad holder is a wax pad 11 over which is placed a cloth 12, the edges of which are clamped in place by a spring keeper 13. 80

It will be noted on reference to the drawings that each pad holder is formed with a plurality of flats 14 on its outer periphery and at each of these flats is provided a support 15. These supports first extend downwardly and then outwardly. The spring keeper rests on these supports 15, but below the level of the lower side of the holder. The keeper therefore between the supports 15 lies partially under the lower edge of the 85 holder and the cloth is thus firmly held between the keeper and the lower edge of the holder.

The ends of the keeper cross and are bent outwardly to form grips 16, and the 95 ends of these grips are so directed that when they are squeezed towards one another they will engage to limit the spreading of the keeper so that there will be no danger of the keeper dropping below the supports 15. 100

The waxing pad is preferably formed of thick felt, and the wax 32, which is moderately soft and which is placed on the pad under the cloth 12, would have a tendency to work into the pad. To overcome this, I provide the pad with a layer 33 of material non-soluble in any of the ingredients of the floor wax, which prevents the pad becoming saturated with wax. A coating of paraffine wax is satisfactory.

In the prior construction, when the device was used for waxing the weight at one end was taken entirely by the ground wheels and at the other end entirely by the waxing pads. As too much wax may thus be forced on to the floor, I find it desirable to relieve the wax pads at times of a portion of this weight. I therefore provide the upper surface of the frame with lugs 17 and between these lugs is pivoted an arm 18, one end of which is forked and has journalled thereon the roller 19. This arm is provided with an integral pin 20 and on this pin is mounted one end of a coil spring 21, the other end of which spring engages in a recess 28 in the frame of the machine. When the device is being used for waxing, this spring actuated roller is in contact with the floor and partially relieves the weight on the waxing pads, though the pressure may be increased as necessary, in the manner hereinafter described. The pivoted end of the arm is provided with a projection 22, which engages the frame and thus holds the spring in the desired state of tension and also prevents the arm being thrown too far out and interfering with the placing of the device in the floor when waxing is to be proceeded with.

The handle bail is formed of two halves one end of each half being pivoted on the side of the casing. Between the other ends of the halves is received the end of the handle 24, a single bolt 25 passing through the ends of the parts of the bail and handle. To hold the handle from rocking on the bolt relative to the bail, I provide at opposite sides of the handle the channel shaped clips 26, which between them substantially encircle the ends of the bail parts and the handle. These clips 26 are held in position by the bolt 25.

On each side of the casing is formed a shoulder 27, which shoulders are engageable by the bail to limit its movement so that the handle may occupy a substantially upright position when the device is not in use. These shoulders in the present construction are formed by making the end of the casing of slightly less width than the remainder of the casing, the shoulders thus being adapted to be engaged by the handle bail no matter which side of the device is uppermost.

A further object in pivoting the handle against the sides of the portion of the frame of lesser width is that the handle does not in

any way interfere with the waxing or polishing of the floors close to the walls, as would be the case if the handle projected beyond the main part of the frame.

It will be noted that the handle is pivoted between the ground wheels and the resilient means for relieving the weight on the waxing pads. If sufficient wax is not being transferred to the floor, it is merely necessary to exert extra pressure on the handle to ensure that the floor is being properly waxed.

A further feature of my invention is the method of mounting the brushes to the tool carrier. In the patented construction referred to, the brushes are firmly secured to the carrier. I find, however, that the brushes are not always exactly the same due to differences in thickness of the back or in the length of the bristles. I therefore secure the brush to the carrier by means of screws 29. I however, interpose between the back of the brush and the carrier a spring 31, which tends to separate the brush and tool carrier, but this separating movement is limited by the engagement of the heads on the screws 29 with the carrier. With the construction described, the brush is free to move to or from the carrier within predetermined limits, but these limits may be easily altered by adjusting the screws 29.

Wear on the brushes may also be taken care of by suitably adjusting the screws 29.

From the above description it will be seen that I have devised a construction which will satisfactorily attain the objects of my invention as set out in the preamble of this specification.

What I claim is:—

1. For use in a floor wlexer, a waxing pad of soft flexible material having its under surface provided with a layer of substantially non-porous material, on the outer surface of which non-porous material the wax is carried; and a porous covering over the wax-coated surface.

2. For use in a floor wlexer, a waxing pad of felt having its under surface coated with a material non-soluble in any of the ingredients of the floor wax, on the outer surface of which non-soluble material the wax is carried; and a porous covering over the wax-coated surface.

3. In a floor wlexer, the combination of a pad holder substantially circular in plan but having a plurality of flats around its periphery; a plurality of supports on said holder, one at each flat, said supports extending first downwardly below the bottom of the holder, and then outwardly; a pad on said holder; a piece of porous material over said pad and extending down the side of the holder; and an expansible spring keeper on said supports adapted to clamp the piece of porous material against the bottom edge of the holder.

4. In a floor waxer, the combination of a pad holder substantially circular in plan but having a plurality of flats around its periphery; a plurality of supports on said holder, one at each flat, said supports extending first downwardly below the bottom of the holder, and then outwardly; a pad on said holder; a piece of porous material over said pad and extending down the side of the holder; and an expansible spring keeper on said supports adapted to clamp the piece of porous material against the bottom edge of the holder, the ends of the keeper overlapping one another and being bent outwardly to form finger grips.

5. In a floor waxer, the combination of a pad holder substantially circular in plan but having a plurality of flats around its periphery; a plurality of supports on said holder, one at each flat, said supports extending first downwardly below the bottom of the holder, and then outwardly; a pad on said holder; a piece of porous material over said pad and extending down the side of the holder; and an expansible spring keeper on said supports adapted to clamp the piece of porous material against the bottom edge of the holder, the ends of the keeper overlapping one another and being bent outwardly to form finger grips, and adapted to engage one another to limit the expansion of the keeper.

6. In a floor waxer, the combination of a tool carrier having shoulders formed thereon; a waxing pad holder; and a spring clip on said pad holder adapted to be detachably engaged with said shoulders to retain the holder in position on the carrier.

7. In a floor waxer, the combination of a tool carrier having shoulders formed thereon; a waxing pad holder; and a spring clip on said pad holder adapted to be detachably engaged with said shoulders to retain the holder in position on the carrier, said tool carrier and waxing pad holder being provided one with a projection and the other with a hole into which the projection may extend.

8. In a floor waxer and polisher, the combination of a frame; ground wheels mounted in the frame adjacent the one end thereof; a waxing pad adjacent the other end of the frame; and resilient means mounted on the frame and engaging the floor to relieve the weight of the frame on the waxing pad.

9. In a floor waxer and polisher, the combination of a frame; ground wheels mounted in the frame adjacent one end thereof; a waxing pad adjacent the other end of the frame; lugs on the frame adjacent the waxing pad; an arm pivoted at one end between said lugs; a roller journalled at the other end of said arm; and a coil spring engaging the frame with one end and the arm with its other end.

10. In a floor waxer and polisher, the combination of a frame; ground wheels mounted in the frame adjacent one end thereof; a waxing pad adjacent the other end of the frame; lugs on the frame adjacent the waxing pad; an arm pivoted at one end between said lugs; a roller journalled at the other end of said arm; and a coil spring engaging the frame with one end and the arm with its other end, said arm being provided with a projection adapted to engage the frame to limit the movement of the arm.

11. In a floor waxer and polisher, the combination of a frame; ground wheels mounted in the frame adjacent one end thereof; a waxing pad adjacent the other end of the frame; lugs on the frame adjacent the waxing pad; an arm pivoted at one end between said lugs; a roller journalled at the other end of said arm; and a coil spring engaging the frame with one end and the arm with its other end, the frame being provided with a recess into which one end of the coil spring extends, and the arm with a projection extending into the other end of the spring.

12. In a floor waxer, the combination of a pad holder; a pad on said holder; a piece of porous material over said pad and extending over the sides of the holder; an expansible spring keeper adapted to clamp the piece of porous material against the edge of the back of the holder; and a plurality of supports extending outwardly from the back of the holder adapted to position the keeper behind the edge of the back of said holder.

13. In a floor waxer, the combination of a pad holder; a pad on said holder; a piece of porous material over said pad and extending over the sides of the holder; an expansible spring keeper adapted to clamp the piece of porous material against the edge of the back of the holder; and supports adapted to position the keeper behind the edge of the back of said holder, the ends of the keeper overlapping one another and being bent outwardly to form finger grips.

14. In a floor waxer, the combination of a pad holder; a pad on said holder; a piece of porous material over said pad and extending over the sides of the holder; an expansible spring keeper adapted to clamp the piece of porous material against the edge of the back of the holder; and supports adapted to position the keeper behind the edge of the back of said holder, the ends of the keeper overlapping one another and being bent outwardly to form finger grips and adapted to engage one another to limit the expansion of the keeper.

15. In a floor waxer and polisher, the combination of a frame; ground wheels mounted in the frame adjacent the one end

thereof; a waxing pad adjacent the other end of the frame; and resilient means mounted on the frame and engaging the floor to relieve the weight of the frame on the waxing pad; and a handle mounted on the frame intermediate the ground wheels and the resilient means.

16. In a floor wlexer, the combination of

a tool carrier; a brush mounted on said carrier; resilient means comprising corrugated metallic plate tending to separate the brush and carrier; and means for limiting the movement of the brush from the carrier. ¹⁰

Signed at Toronto this 23 day of July 1923.

JOHN T. GARTON.
